UNITED STATES PATENT OFFICE

134,632

DESIGN FOR A PATRIOTIC VICTORY BANNER

Ethyl L. Hubin, Faribault, Minn.

Application November 4, 1942, Serial No. 108,693

Term of patent 14 years

To all whom it may concern:

Be it known that I, Ethyl L. Hubin, a citizen of the United States, residing at Faribault, in the county of Rice and State of Minnesota, have invented a new, original, and ornamental Design for a Patriotic Victory Banner, of which the following is a specification, reference being had to the accompanying drawing, forming part thereof.

In the drawing:

I claim:

The ornamental design for a patriotic victory banner, substantially as shown.

ETHYL L. HUBIN.
